UNITED STATES PATENT OFFICE.

ELI BROTHERS, OF LYNN, MASSACHUSETTS, ASSIGNOR TO UNITED SHOE MACHINERY COMPANY, OF PATERSON, NEW JERSEY, A CORPORATION OF NEW JERSEY.

MACHINE FOR WORKING AN UPPER OVER A LAST.

1,055,016.

Specification of Letters Patent.

Patented Mar. 4, 1913.

Application filed September 23, 1908. Serial No. 454,440.

To all whom it may concern:

Be it known that I, ELI BROTHERS, a citizen of the United States, residing at Lynn, in the county of Essex and Commonwealth of Massachusetts, have invented certain Improvements in Machines for Working an Upper Over a Last, of which the following description, in connection with the accompanying drawings, is a specification, like reference characters on the drawings indicating like parts in the several figures.

This invention relates to machines for use in making shoes and particularly to machines for pulling over shoes. These machines are employed for initially stretching, positioning, and, it may be, fastening also, an upper on a last preliminary to the lasting operation by which the pulled-over upper is more completely conformed to the shape of the last. These machines usually comprise grippers for engaging and pulling an upper at the opposite sides of the fore part of the shoe simultaneously, and have means for relatively moving the side grippers lengthwise of the shoe to adjust the upper longitudinally around the last. It is by this adjustment that the toe tip seam or line is correctly positioned with relation to the last and this adjustment is commonly referred to as the "tip straightening" adjustment, while the mechanism for producing this movement of the side grippers is referred to as the "tip straightening" mechanism. This type of machine is shown and fully described in United States Letters Patent No. 1,029,387, granted June 11, 1912, on an application filed March 28, 1903, by Ronald F. McFeely. The present invention is shown as applied to a machine similar to that of said patent and reference may be had to the patent if a more full explanation of the machine is desired than seems necessary to give in describing the present improvement. In the use of that machine, the upper is first pulled so that its position on the last can be ascertained and then the machine comes automatically to rest while the upper is held under tension to permit the side grippers to be relatively moved as may be required for straightening the tip. The close engagement of the pulled upper with the last while it is so held prevents it from responding readily to the tip straightening

movement of the grippers and in the manufacture of heavy shoes, particularly on certain styles of lasts, it is necessary to put a very heavy tension on the upper in pulling over the shoe in order to pull the upper down to the wood over the ball of the last. The adhesion of the upper materials to the top face of the last over which they are so pulled prevents the upper at this point from responding to the tip straightening movement of the grippers and results, to a greater or less degree, in bending the tip seam into a somewhat S shaped line.

It is the object of this invention to facilitate the tip straightening operation, and to this end a very important feature of the invention consists in means for relieving the tension on the upper while the tip is being straightened. In the illustrated embodiment of the invention, means is provided for depressing the grippers enough to reduce the tension on the upper so that the tip can be straightened without distorting or straining the upper. The tension relieving means is shown as arranged under control of the operator so that the grippers can be lowered as much as may be required in each instance to permit the upper to be adjusted lengthwise about the last. The grippers in the illustrated machine are automatically uplifted for pulling the upper through levers having yielding connections with an operating cam. I have provided manually operated means for engaging the rear ends of the levers to lower the side grippers against the pressure of said yielding connections which will restore the tension on the upper as soon as the operator permits after the tip has been straightened. The tension relieving means may conveniently be actuated through a foot treadle which will leave the operator's hands free for manipulating the tip straightening mechanism or for other purposes. It sometimes happens that the upper can advantageously be stretched more than is done by the automatic operation of the machine. In accordance with this invention, the upper can be again pulled by depressing the grippers by means of the treadle and then permitting the yielding connections between the operating cam and the gripper levers to lift them, whereupon it will be found that additional stretch will

have been taken out of the leather. This can be done repeatedly until the upper has been pulled as much as may be desired.

It is a new feature of this invention to provide, in an automatically-operated machine, operative connections from an actuator to the two side grippers by which they can be manipulated together to pull the upper a second time or to pull the upper repeatedly. If the operator fails to put the upper into the machine so that the two sides are pulled equally, or if for any other reason it is desirable to rearrange the upper in the side grippers, the treadle connections can be manipulated to lower the grippers into engagement with their opening mechanism which is fully shown and described in said prior patent, thereby causing them to release the upper and giving opportunity for the upper to be readjusted that the grippers at one or both sides will seize it at a new point to pull it more or less. Also, if desired, the grippers may be moved relatively lengthwise of the last by the tip straightening mechanism so that they will reengage and pull the upper at new points. The tension on the toe of the upper may be relaxed to facilitate the adjustment of the upper by pulling down the handle end of the toe gripper lever. When the grippers are released from the upper the shoe is held in position in the machine by the heel rest and by the engagement of the toe gripper with the toe end of the upper. If it should be found that the upper is so incorrectly positioned upon the last that it cannot be readjusted or if for any reason it becomes desirable to remove the shoe from the machine without fastening the upper by the tacking inserting mechanism which is arranged to operate automatically at the second treading of the machine, then, in such case, the toe gripper may be depressed by the handle of its operating lever to open said toe gripper and thus free the shoe from the machine before the tacking mechanism is actuated. This saves driving tacks in the shoe and pulling them out again.

A further feature of this invention is found in the provision, for example, in the mechanism above referred to, of means by which the operator can control the rate at which the actual updraw movement of the said grippers, initiated by the power mechanism of the machine, shall take place. By this feature of the invention the operator is enabled to watch the progress of the upper-pulling movement as it takes effect upon the upper and to arrest that movement at any desired point in the stroke normally effected by the power mechanism. By this means the upper may be slowly stretched as compared with the stretching heretofore effected by power machines whereby the stretching may be more thoroughly done

without danger of tearing the upper. To obtain these results I employ the manually operated means, which engages the rear ends of the gripper updraw levers, to retard or to delay the depression of the rear ends of said levers during the rotation of the lever actuating cam, thereby causing the power initiated by the cam to be stored in the springs which connect the rear ends of the levers with the cam. Then by allowing those springs to expand under control of the manually operated means I effect the desired rate and extent of pulling or stretching of the upper, terminating that movement whenever the operator sees that the individual shoe being treated has been stretched to the proper degree.

These and other features of this invention, including certain details of construction and combinations of parts will appear in connection with the following description of a preferred embodiment of the invention, as applied to a machine of the type shown in said prior patent.

In the drawings:—Figure 1 is a side view of the machine equipped with this invention; Fig. 2 is a perspective view showing the tension relieving mechanism.

The machine has a driving shaft 2 supported in the head and having cams 4 and 5 near its rear end with which are connected the slides 6 and 8 from which project rods 7 and 9. These rods are encircled by springs 10 and 12 held under tension between adjustable nuts 11 and 13 and the rear ends of gripper levers 14, 15 and 16, or knuckle blocks in which said rear ends are held to facilitate their movements. As will be seen from Fig. 2, the slide 6 has two rods 7 connected with the two side gripper levers 14 and 16. The levers are all pivoted on the rod 17 and from their front arms are suspended by universal joints the grippers 18, 19 and 20. These grippers are fully shown and described in said prior patent wherein it is explained that they are guided in the bracket 21 upon the upper surfaces of which the shoulders 22 are adapted to catch as the grippers are depressed, whereby the opening of the gripper jaws is effected. The side grippers 18 and 20 are both connected to the hand lever 25, as also fully explained in said patent, by the pinion shaft 26 which is engaged on its upper side by a rack bar 28 connected to the gripper 18 and is engaged on its lower side by a rack bar 30 connected with the gripper 20. Through these connections the two side grippers may be moved simultaneously in opposite directions lengthwise of the last for adjusting the upper longitudinally about the last to straighten the toe tip seam, or position it in desired relation to the last. The shoe is rested in position to be operated upon by the heel rest 32 and the sole rest 34. The ma-

chine is provided with manually controlled starting mechanism by which the shaft is caused to rotate until the grippers have seized the upper and pulled it, whereupon 5 automatically operating stopping mechanism brings the machine to rest with the upper held under tension as shown in Fig. 2. This is preferably the same starting and stopping mechanism as that described in 10 said prior patent.

The new parts added to the machine to embody the present invention include the treadle 40 located in the base of the machine and connected by the rods 42 and slides 44 15 with the rear ends of side gripper levers 14 and 16, as shown best in Fig. 2. The slides have curved slots which receive the pins 45 on the levers 14 and 16 and permit said levers to move freely in their automatic 20 actuation without disturbing the treadle. Depression of the foot plate of the treadle effects the uplifting of the rear ends of the levers 14 and 16 and the depression or lowering of the side grippers, the springs 10 25 yielding or being compressed by this movement of the levers and re-acting to move the levers and the grippers reversely when the treadle is released.

The new mechanism provides means by 30 which, when the upper is held under tension, the side grippers may be moved relatively to the last to relieve the tension on the upper. The extent of this movement may be determined by the operator. For example he can relieve the tension enough to 35 permit the upper to respond readily to the adjusting movements of the grippers lengthwise of the last for straightening the tip by the lever 25 and then release the treadle to 40 let the grippers pull the upper in its straightened position. The side grippers may be depressed to slacken the upper and then permitted to rise under the influence of the compressed springs 10 to tighten the 45 upper. This successive slackening and pulling of the upper can be effected repeatedly to stretch the upper as much as may be desired. If the shifting of the grippers lengthwise of the last does not satisfactorily adjust 50 the upper, the grippers may be lowered until by the engagement of their shoulders 55 with the bracket 21 the jaws are opened and opportunity is given to readjust the upper in the grippers and relatively to the last. Adjustment of the upper can at this time be made lengthwise of the last and also transversely of the last. When the 60 treadle is permitted to rise the side grippers will reengage the upper at new points and pull it in its adjusted position. While the side grippers are released from the upper, the shoe is held by the heel and sole rests and by the toe gripper. The lever 15 for the toe gripper has a handle on its front 65 end, by which the toe gripper may be pulled

down to relax the tension applied by it to the upper while the two side grippers are depressed together by the foot treadle. It is a characteristic feature of the illustrated embodiment of this invention which is of great practical importance that the two side grippers are depressed together without the use of the operator's hands, thus leaving both his hands free for use for other purposes, and enabling him to effect operations and make adjustments heretofore impossible. By the expression "means for effecting a movement of a plurality of pairs of grippers simultaneously in the direction to relieve the tension on the pulled upper," and by similar expressions as used in the claims, I do not of course intend or desire to include the construction shown in U. S. Letters Patent No. 663,777, dated December 11, 1900, comprising handles on the front ends 70 of the gripper actuating levers by which, using both of his hands, the operator may depress both of the gripper carrying levers. It is, however, new with me to provide means constructed and located for convenient actuation by any one of the operator's limbs for causing simultaneous movement of the side grippers to relax the tension on the upper. If it is found that the shoe and last cannot be properly adjusted in the machine, or that for any reason it is desirable to remove the shoe without fastening the upper, the toe gripper as well as the side grippers can be depressed to release the upper and permit the shoe to be taken away from the 80 machine before the tack driving mechanism, which is like that of said patent, is operated. This saves the unnecessary and wasteful procedure heretofore practised of driving the tacks into the shoe and then pulling them out from an improperly pulled shoe. 90

Having set forth the nature of this invention, described a construction embodying the same in the best form now known to me and explained how I have contemplated employing it although without attempting to anticipate all the uses which it may serve, I claim as new and desire to secure by Letters Patent of the United States:—

1. A machine of the class described, having in combination, a plurality of pairs of grippers and automatic mechanism for causing the grippers to pull simultaneously and hold under tension the upper at opposite sides of a last, and manually controlled means for effecting a movement of a plurality of pairs of grippers simultaneously in the direction to relieve the tension on the pulled upper. 115

2. A machine of the class described, having in combination, grippers, means including a yielding element to actuate the grippers to pull an upper and hold it under tension, and means arranged for manual operation to move a plurality of the grippers re- 120 125 130 135

versely together against the tension of said yielding element for temporarily relieving the tension on the upper.

3. A machine of the class described, having in combination, a gripper, automatically operating means for causing the gripper to seize the upper, pull it over a last and hold it under tension, means for relatively moving the gripper and the last to adjust the upper on the last, a treadle and connections therefrom to enable the operator to move the gripper and the last relatively to relieve the tension on the upper during the adjusting operation.

15 4. A machine of the class described, having in combination, a gripper, automatically operating means for causing the gripper to seize the upper, pull it over a last and come to rest holding the upper under tension, a treadle and connections therefrom to enable the operator to move the gripper and the last relatively to relieve the tension while leaving his hands free.

25 5. A pulling over machine having in combination, grippers for engaging the upper at opposite sides of the fore part of a shoe to pull the upper and hold it under tension, means for moving the grippers and the last relatively to straighten the toe tip seam, 30 and means including a treadle, for relieving the tension on the upper during the tip straightening operation.

35 6. A pulling over machine having in combination, side grippers, manually operable tip straightening means, and means including a single actuating member, adapted for movement by the operator to relieve the tension on the upper during the operation of the tip straightening means.

40 7. A pulling over machine having in combination, side grippers, means including yielding elements for uplifting the grippers to pull the upper and hold it under tension, said machine having provision for relatively 45 moving the grippers and the last to adjust the upper on the last, and a single means adapted for lowering the grippers for the opposite sides of the last together against the tension of the yielding elements.

50 8. A pulling over machine having in combination, side grippers, levers therefor, independently yielding connections between said levers and an automatically operated driving element to impart normal movements to the grippers, a treadle and connections therefrom to the levers for imparting additional movements to the grippers.

55 9. A pulling over machine having in combination, two grippers for engaging an upper at the opposite sides of a last, said grippers being free for independent movements and having means by which said movements may be effected to adjust the upper, automatic means for actuating the 60 said side grippers to pull the upper and

then come to rest holding the upper under tension, and manually controlled means operatively connected with the side grippers and including a single member which is adapted for actuation to open both of said 70 grippers.

10. A pulling over machine having in combination, two grippers for engaging an upper at the opposite sides of a last, said grippers being free for independent movements and having means by which said movements may be effected to adjust the upper, automatic means for actuating the said side grippers to seize the upper, pull it and hold it under tension, and means, including a single actuating member, operatively connected with both side grippers and arranged for manual actuation to relieve the tension on the upper and, if desired, to open the grippers.

15 11. A pulling over machine having in combination, two grippers arranged to engage an upper at opposite sides of a last, said grippers being free for independent movements and having means by which said movements may be effected to adjust the upper, automatic means for actuating said side grippers to pull the upper and hold it under tension, manually controlled means, including a single actuating member, connected with both side grippers to move them reversely to the pulling movement and open them, and means for adjusting the grippers lengthwise of the upper, said machine having provision for causing the grippers to reengage the upper in their adjusted positions.

20 12. A pulling over machine having in combination, two grippers arranged to engage an upper at opposite sides of a last, said grippers being free for independent movements and having means by which said movements may be effected to adjust the upper, automatic means for actuating said side grippers to pull the upper and hold it under tension, and means operatively connected with both side grippers for causing movement of said grippers together to relax and then renew the tension on the upper.

25 13. A pulling-over machine having, in combination, two grippers arranged to engage an upper at opposite sides of a last, automatic means for actuating said side grippers to pull the upper and hold it under tension, and means constructed and located 110 for convenient actuation by one of the operator's limbs for causing simultaneous movement of the grippers to relax the tension on the upper.

30 14. A pulling over machine having in combination, two grippers arranged to engage an upper at opposite sides of a last, said grippers being free for independent movements and having means by which said movements may be effected to adjust the 125 130

upper, automatic means for actuating said side grippers to pull the upper and hold it under tension, and means including a single actuating member to control both side grippers, arranged for manual operation to cause said grippers to relax and renew the tension on the upper repeatedly.

15. A pulling over machine having in combination, two grippers arranged to engage an upper at opposite sides of a last, automatic means for actuating said side grippers to pull the upper and then come to rest holding the upper under tension, said means including levers for the grippers, an actuator and yielding connections between the levers and the actuator, a treadle and connections between the treadle and said levers for lowering the grippers independently of the automatic operation of the machine.

20. 16. A pulling over machine having in combination, grippers arranged to engage an upper at opposite sides and at the toe of a last and automatically operating means for actuating said grippers to seize the upper, pull it and hold it under tension, means, including a single actuating member, under control of the operator and operatively connected with both side grippers for lowering the side grippers to relieve their tension on the upper, and if desired to open them, and other means by which the operator can lower and if desired open the toe gripper.

25. 17. A pulling over machine having in combination, grippers arranged to engage an upper at opposite sides and at the toe of a last, automatically operated means for actuating said grippers to seize the upper, pull it and hold it under tension, means for inserting tacks to fasten the upper when the machine is restarted, and means, including a single actuating member, by which the grippers can be opened together to permit the shoe to be removed from the machine

45. 18. A pulling-over machine having, in combination, grippers arranged to engage an upper at opposite sides and at the toe of a last, means for moving the grippers to put the upper under tension, connecting means to provide for reversely moving the side grippers together to relax the tension under which the upper is held by them, and a heel rest coöoperating with the toe gripper 50 to sustain the shoe when the tension applied by the side grippers is relaxed.

40. 19. A pulling-over machine having, in combination, grippers arranged to engage an upper at opposite sides of a last, a shoe bottom rest, means for actuating the grippers to seize the upper, pull it and hold it under tension, said machine having provision for relative movement of the side grippers and the last for adjusting the upper on the last, means for relaxing the ten-

sion on the upper held by the side grippers while said adjustment is being effected, and means for engaging the shoe at the toe and heel ends to prevent unintentional displacement of the shoe during the adjustment of the upper.

20. A machine of the class described having, in combination, grippers for engaging the upper and automatic actuating mechanism to cause the grippers to pull the upper and come to rest holding the upper under tension, manually operable means for moving the grippers to adjust the pulled upper on the last, and means in addition to the automatically actuated mechanism for enabling an operator to move the grippers together in the direction to relax the tension on the pulled upper while the adjustment of the upper is being effected.

25. 21. In a pulling-over machine the combination with oppositely disposed side grippers and power mechanism for operating them, of means, including a single actuating member arranged to be controlled by the operator while the pulling movement is taking place to determine the extent to which the upper shall be pulled.

30. 22. In a pulling-over machine the combination with oppositely disposed side grippers and power mechanism for operating them including the levers 14 and 16, the springs 10, the slide 6 and the cam 4; of the treadle 40 and connections 42, 44, 45 with the levers 14, 16, said treadle and connections being arranged and constructed to enable the operator by his foot upon the treadle to retard the movement of the levers and cause the springs 10 to be compressed by movement of the cam and then allow the springs to expand for moving the grippers slowly to pull the upper after the cam may have come to rest.

35. 23. In a pulling-over machine the combination with oppositely disposed side grippers and power mechanism for operating them, of means, including a single actuating member, which may be employed by the machine operator at will to modify the rate at which the power driven side gripper pulling movement shall take effect.

40. 24. In a pulling-over machine the combination with oppositely disposed side grippers and power mechanism for operating them, of yielding connections between the grippers and said mechanism, and a single actuator and connections controllable manually during the pulling movement to govern the rate at which the movement initiated by the power shall be transmitted to the grippers.

45. 25. In a pulling-over machine the combination with oppositely disposed side grippers and power mechanism for operating them, of yielding connections between the grippers and said mechanism, and means by

which the movement of the grippers can be delayed while the power becomes stored in the yielding connections to be released at the will of the workman for continuing the movement of the grippers.

26. In a pulling-over machine the combination with oppositely disposed side grippers and power mechanism for operating them, of a single actuator and connections controlled by the operator while the pulling movement is taking place and by which he can govern the progress of the pulling movement and arrest it at any desired point within the stroke of the grippers normally effected by the power mechanism.

27. A pulling-over machine having, in combination, toe and side grippers, power operating mechanism therefor, and means under control of the operator to delay the operation of the side grippers relatively to the operation of the toe gripper.

28. A pulling-over machine having, in combination, toe and side grippers, power operating mechanism therefor, and a single means under control of the operator to suppress temporarily the operation of the side grippers, substantially as described.

29. A pulling-over machine having, in combination, toe and side grippers, power operated mechanism therefor, and a single means under control of the operator to prevent the power operated mechanism from taking effect upon the side grippers until after the normal point in the cycle of the machine at which the side grippers are moved.

30. A pulling-over machine having, in combination, toe and side grippers, power operated mechanism arranged to cause the seizing and pulling of the upper by the toe and side grippers normally to occur in a pre-determined order, and a single means under control of the operator to delay the seizing of the upper by one of said pulling members until a selected time.

31. A pulling-over machine having, in combination, a plurality of grippers, power actuated mechanism therefor, and a single means by which the operator can assume control of the pulling movement of the grippers effected by the power and retard or arrest such movement at will.

32. A pulling-over machine having, in combination, a plurality of grippers arranged to engage and pull an upper over a last at one operation, power actuated mechanism for said grippers and means constructed and located for convenient actuation by one of the operator's limbs whereby the operator can regulate and limit, while the machine is running, the upper pulling movement effected by said power mechanism in accordance with the requirements of the individual shoes, substantially as described.

In testimony whereof I have signed my name to this specification in the presence of two subscribing witnesses.
